UNITED STATES PATENT OFFICE

155,423

DESIGN FOR A PLATE OR SIMILAR ARTICLE

George J. Higginson, Mount Vernon, N. Y., assignor to Johnson Bros. (Hanley) Ltd., New York, N. Y., a corporation of Great Britain

Application April 2, 1947, Serial No. 138,103

Term of patent 14 years

(Cl. D44—15)

To all whom it may concern:

Be it known that I, George J. Higginson, a citizen of the United States, residing in Mount Vernon, county of Westchester, and State of New York, have invented a new, original, and ornamental Design for a Plate or Similar Article, of which the following is a specification, reference being had to the accompanying drawing, forming a part thereof.

The single figure is a top plan view of a plate or similar article, showing my new design, the essential features of which reside in the floral decoration in the center of the plate.

I claim:

The ornamental design for a plate or similar article, as shown and described.

GEORGE J. HIGGINSON.
